ATTORNEY.

UNITED STATES PATENT OFFICE

PORTIS P. SHAW, OF ST. LOUIS, MISSOURI

LUBRICATING DEVICE

Application filed July 27, 1932. Serial No. 624,999.

My invention relates to lubricating devices, and more particularly to means for automatically lubricating the valve stems and upper cylinder surfaces of internal combustion engines.

The object of my invention is the provision of a device for supplying small quantities of special lubricant from a container to the intake manifold of an internal combustion engine, so that the flow of combustible mixture of gas and air through the intake manifold passing the valves and into the combustion chambers of the engine cylinders will carry therewith the desired quantities of vaporized lubricant for automatically lubricating said engine parts.

A further object of the invention is the provision of a supporting bracket to which the container having the lubricant can be readily attached, and when the container is empty, can be readily removed and a new container filled with lubricant quickly attached to said bracket.

A further object of the invention resides in the provision of a conduit leading from the bracket to and having connection with the intake manifold of an internal combustion engine, said conduit being provided with a suitable wick, barely protruding into the intake manifold at one end and extending through and beyond the bracket at its opposite end so that it can be submerged in a depending state in the lubricant of a container which is suspended from said bracket.

A further object of the invention is to provide a wick which is larger in body size than that portion of the wick receivable in the conduit.

A still further object of the invention is the provision of a conduit having a coil formed intermediate its ends.

A still further object of the invention is the provision of a lubricating device which possesses advantages in points of simplicity and efficiency, and, at the same time proves itself comparatively inexpensive in cost of manufacture.

With the above and similar objects in view, the invention consists in the novel arrangement, construction and combination of parts

hereinafter more fully described and finally pointed out in the claims hereto appended.

Referring to the accompanying drawing forming a part of this specification, wherein like characters of reference denote similar parts throughout the several views:

Fig. 1 is a view partly in side elevation and partly in section showing the lubricating device embodying the features of my invention.

Fig. 2 is a detail showing the end of the lubricant feed wick communicating with the interior of the intake manifold as bound by suitable windings to condense the wick material.

Referring to the drawing, the reference character A designates a suitable support, such for instance as the dash, or similar support of an automobile, aeroplane, motor boat, or the like, while the reference character B designates an intake manifold, only a portion of which is shown.

In carrying out the aim of my invention, I employ a suitable bracket which embodies a suitable head 1, from which laterally extends an arm 2 provided with a foot 3 directed from either side thereof, and which foot is provided with openings 4 through which suitable fastening devices 5 pass for securing the bracket to the support A.

The bracket head 1 is shown as provided with a suitable passage 6 which communicates at its lower, or inlet end with an enlarged vertically disposed internally screw threaded recess 7.

A suitable conduit 8, such as copper tubing, is connected at its one end, through the medium of a suitable fitting 9 with the bracket head 1. The fitting 9 has screw threaded connection with the outlet end of the bracket head passage 6. The opposite end of the conduit 8 is connected, through the medium of a suitable fitting 10, with the intake manifold B, preferably by the fitting 10 having screw threaded connection with an opening 11 in the wall of the manifold B. The location of the fitting 10 is preferably midway the ends of the intake manifold.

The conduit 8 is preferably, although not necessarily provided with a depending loop,

or coiled section 12 intermediate its ends. The loop is preferably formed in a horizontally disposed section of the conduit.

A suitable fibrous wick, such for instance, as a woolen wick is employed and that portion of the wick designated 13 is carried by, or receivable in the conduit 8 and its fittings 9 and 10. The outlet end of the wick passing through fitting 10 is preferably, although not necessarily bound with thread, or like binding material 14 so as to condense the material adjacent the fitting 10. The outlet end of the wick preferably protrudes beyond the outlet end of the fitting 10 and enters the passage 15 of the intake manifold B so that the rapid movement of the combustible mixture passed the protruding end of the wick will have a tendency to wipe lubricant therefrom in uniform quantity to be carried with the combustible mixture entering the engine cylinders, as is manifest.

The wick 13 passes through the bracket head opening 6 and the remaining portion of the wick which is designated 16, depends from the bracket head passage 6. This portion 16 of the wick is preferably larger in diameter than portion 13 thereof to provide a rapid feed to wick portion 13.

The wick portion, or section 16 depends from the bracket head 1 and is receivable in a container C which is supplied with a suitable lubricant 17. This latter portion of the wick is of sufficient length to lie on the bottom of the container so that a sufficient length of the wick will always be thoroughly saturated with lubricant even when the container becomes nearly empty.

The container C is provided with a suitable screw threaded neck 18 which has screw threaded connection with the screw threaded recess 7 of the bracket head 1 and a suitable packing having a wick opening 19 is disposed between the open end of the container neck and the base of the recess 7 so as to prevent leakage between the container neck and the bracket recess 7.

The container is readily detachable from the bracket head 1 and assumes a vertical suspended or hanging position relative to the bracket head 1. When the screw threaded container neck 18 has been turned into a tight home position in the screw threaded recess 7, the container is securely held against accidental rotation and will not become loose in its connection with the bracket head 1, except by manual force being applied to the can body.

From the foregoing description, read in connection with the drawing, it is apparent, that the suction exerted through the intake manifold and flexible conduit with the wick therein creates a vacuum in the conduit bracket head passage and the container and together with the heat developed by the en-

gine when running, assists the movement of lubricant along the wick from the container, which, when it reaches the outlet end of the wick is wiped or carried off the outlet end of the wick to be mixed and carried along with the combustible mixture into the upper ends of the engine cylinders, thereby lubricating all engine parts in contact therewith in its travel to and into the engine cylinders from the intake manifold.

The many advantages of the herein described invention will readily suggest themselves to those skilled in the art to which it appertains.

From the foregoing description, it is evident that a simple device for this purpose has been disclosed, but it is to be understood that I do not desire to restrict, or limit myself to the very details of the construction shown and described, which is merely illustrative, it being obvious that changes, not involving the exercise of invention, may be made without conflicting or departing from the spirit of the invention within the scope of the appended claims.

What I claim is:

1. A lubricating device for internal combustion engines having an intake manifold, a bracket having a head provided with a passage and a screw threaded recess, a lubricant container detachably connected with the screw threaded recess of the bracket head and depending therefrom, a flexible tubular conduit connecting the outlet end of the bracket head passage with the intake manifold, a wick passing through said conduit, said head passage and entering the lubricant container to be submerged in the lubricant of the container.

2. A lubricating device for internal combustion engines having an intake manifold, a bracket having a head provided with a passage and a screw threaded recess, a lubricant container detachably connected with the screw threaded recess of the bracket head and depending therefrom, a flexible tubular conduit connecting the outlet end of the bracket head passage with the intake manifold, a wick passing through said conduit, said head passage and entering the lubricant container to be submerged in the lubricant of the container and said flexible conduit having a coil formed intermediate the ends thereof.

3. A lubricating device for internal combustion engines having an intake manifold, a bracket having a head provided with a passage and a screw threaded recess, a lubricant container detachably connected with the screw threaded recess of the bracket head and depending therefrom, a flexible tubular conduit connecting the outlet end of the bracket head passage with the intake manifold, a wick passing through said conduit, said head passage and entering the lubricant

5 container to be submerged in the lubricant of the container and said flexible conduit having a coil formed intermediate the ends thereof and depending from a horizontal section of the conduit to serve as a lubricant trap between the engine manifold and the bracket head.

4. In an overhead lubricating device for internal combustion engines, a bracket including a foot and a head, means for securing said foot to a support, said head having a passage therethrough, a conduit leading from the outlet end of said passage to and connected with the intake manifold of the engine, a lubricant container detachably secured to the head and suspended therefrom and having communication with the inlet end of said passage, and a wick receivable in said conduit, said head and directed at one end into said container and at its opposite end into the passage of the intake manifold.

5. In an overhead lubricating device for internal combustion engines, a bracket including a head, a foot on said head, means for securing said foot to a support, said head having a passage therethrough, the lower end of said passage being enlarged to form a recess provided with screw threads, a flexible conduit having detachable connection at one end with the opposite end of said passage and having connection at its opposite end with the intake manifold of the engine, a lubricant container having a screw threaded neck for detachable connection with the screw threaded recess of the head passage so that the container will be suspended therefrom from said head and a wick receivable in said conduit, said head passage and directed at one end into the container to be saturated with lubricant to be fed from the container along the wick for introduction into the intake manifold in uniform quantity when the engine is running.

6. In combination with an intake manifold of an internal combustion engine, of a head having a passage therethrough, a foot on said head for fixed connection with a support, a flexible conduit connecting one end of said head passage with and in communication with the interior of the intake manifold, a detachable lubricant container suspended from said head and communicating with said head passage, a wick in said conduit and extending from the interior of the intake manifold to and through the passage of said head so as to provide a free depending section to be directed into the lubricant of the container.

7. In combination with an intake manifold of an internal combustion engine, of a head having a passage therethrough, a foot on said head for fixed connection with a support, a flexible conduit connecting one end of

said head passage with and in communication with the interior of the intake manifold, a detachable lubricant container suspended from said head and communicating with said head passage, a wick in said conduit and extending from the interior of the intake manifold to and through the passage of said head so as to provide a free depending section to be directed into the lubricant of the container and the outlet end of said wick being bound to condense the material thereof for protrusion into the passage of the intake manifold.

8. In combination with an intake manifold of an internal combustion engine, of a head having a passage therethrough, a foot on said head for fixed connection with a support, a flexible conduit connecting one end of said head passage with and in communication with the interior of the intake manifold, a detachable lubricant container suspended from said head and communicating with said head passage, a wick in said conduit and extending from the interior of the intake manifold to and through the passage of said head so as to provide a free depending section to be directed into the lubricant of the container, the outlet end of said wick being bound to condense the material thereof for protrusion into the passage of the intake manifold and said conduit being provided with a coil intermediate its ends to provide a lubricant trap when the engine stops running.

9. In combination with an engine having an intake manifold, a bracket adapted to be secured to a support, a head on said bracket having a passage therethrough, a lubricant container detachably connected with and depending from said head and communicating with the lower end of said passage, a conduit connecting the intake manifold with the outlet end of the passage of said head, a wick receivable in said conduit, the passage of said head and said lubricant container and that portion of the wick receivable in the container being larger in diameter than that portion of the wick receivable in the conduit.

10. In combination with an engine having an intake manifold, a bracket adapted to be secured to a support, a head on said bracket having a passage therethrough, a lubricant container detachably connected with and depending from said head and communicating with the lower end of said passage, a conduit connecting the intake manifold with the outlet end of the passage of said head, a wick receivable in said conduit, the passage of said head and said lubricant container and that portion of the wick receivable in the container being larger in diameter than that portion of the wick receivable in the conduit, the end of said wick adjacent the intake manifold being bound to condense the material thereof and protrud-

ing into the passage of the intake manifold.

11. In combination with an engine having an intake manifold, a bracket adapted to be secured to a support, a head on said bracket

5 having a passage therethrough, a lubricant container detachably connected with and depending from said head and communicating with the lower end of said passage, a conduit connecting the intake manifold with the out-

10 let end of the passage of said head, a wick receivable in said conduit, the passage of said head and said lubricant container and

that portion of the wick receivable in the container being larger in diameter than that portion of the wick receivable in the conduit, the end of said wick adjacent the intake manifold being bound to condense the material thereof and protruding into the passage of the intake manifold and a coil formed in a section of the conduit to provide a lubricant trap when the engine has stopped running.

70 In testimony whereof, I have hereunto affixed my signature.
